UNITED STATES PATENT OFFICE.

CHARLES STEPHENS, OF LONDON, ENGLAND.

MACHINE FOR DRYING LEATHER, YARNS, JUTE, AND LIKE MATERIALS.

1,384,359.

Specification of Letters Patent. Patented July 12, 1921.

Application filed November 14, 1918. Serial No. 262,626.

To all whom it may concern:

Be it known that I, CHARLES STEPHENS, a subject of the King of Great Britain and Ireland, residing at London, England, have 5 invented a new and useful Improvement in Machines for Drying Leather, Yarns, Jute, and like Materials, of which the following is a specification.

This invention relates to an improved 10 continuous drying machine, of the type in which the material is passed through a horizontal drying chamber by means of a conveyer and subjected during such passage to the action of a heated current of air, for 15 "sammying" and drying leather, and for drying yarns, jute, or any other similar material.

Drying machines of this type have been proposed in which internal transverse baffles above and below the conveyer are arranged to divide the chamber into compartments and to cause the current of air, induced and exhausted by fans at opposite ends of the chamber respectively, to take a 25 sinuous upward and downward path in stages from end to end of the chamber, in a direction opposite to the traverse of the material, and to pass through the material from opposite sides, this current of air during its passage through the chamber being 30 gradually raised in temperature by a separated series of heating batteries arranged in staggered relationship within or between the compartments above and below the conveyer.

My present invention consists in a drying machine of the type described, in which the material is traversed both in forward and return directions through the chamber, and 40 in which a closed circulation of air, giving one continuous cross-current in an upward or downward direction through both lines of material from end to end of the chamber, is maintained by means of a fan or blower in conjunction with air ducts extending from 45 end to end along the top and bottom of the chamber respectively, and in conjunction with flat sets of steam or other coils interposed respectively between the chamber and 50 said air ducts; a further feature of my invention consists in a baffle plate device fitted between adjacent pairs of tubes forming the coils, whereby the circulating air is directed either vertically or obliquely through the 55 chamber and whereby a certain pressure is held back in the air inlet duct so as to equal-

ize the cross-current of air throughout the entire length of the chamber; and a still further feature of my invention consists in the continuous extraction or condensation of 60 moisture from the closed circulation of air within the chamber.

Description of accompanying drawings.

Figure 1 is a front elevation of the machine with parts of casing removed. 65

Fig. 2 is an end elevation of machine with end casing and part of internal bulkhead removed.

Fig. 3 is a plan of machine with parts of 70 cover removed.

Fig. 4 is an enlarged detail elevation of coils and baffles as shown in Fig. 1.

Fig. 5 is an enlarged cross-section of one 75 of the tubular clip bars for supporting material on the conveyer chains.

My improved machine consists firstly of a long horizontal drying chamber A, fitted internally with two flat sets of coils B and C, at short distances from the top and bottom 80 of the chamber respectively, between which coils a closed circulation of air is maintained by means of a fan or blower D, in conjunction with an air-pressure inlet duct E extending from end to end along the bottom 85 of the chamber and an air-suction outlet duct F likewise extending from end to end along the top of the chamber (or vice versa).

Between each adjacent pair of tubes forming the coils B and C is fitted a baffle plate 90 G, by which the circulating air is directed upward or downward either vertically or obliquely through the chamber A, and by which a certain pressure is held back in the air inlet duct so as to equalize the cross-current of air throughout the entire length of the chamber. For ordinary drying purposes the coils B and C are steam-heated, so that the closed circulation of air, on being brought by the baffle plates into intimate 95 contact with the steam coils, is continuously heated and reheated as it circulates. A smaller exhaust fan H is fitted at one end of the chamber to continuously extract from the closed circulation of air a predetermined 100 proportion of the moist air, and an auxiliary set of coils I may be provided to serve either for condensing the moisture or for raising or lowering the temperature of the air circulation, according to requirements. 105

For special processes where a cold or low-temperature air circulation is required, the 110

coils B and C, instead of being steam-heated, may be used at any ordinary low temperature, or even as refrigerator coils. In this case the auxiliary coils I provide for 5 any necessary variations in the working temperature of the machine.

The material under treatment is drawn longitudinally through the machine, between the two sets of steam coils B and C, and in 10 forward and return directions, by any ordinary conveying devices, as for instance by means of a pair of toothed endless chains J carrying transverse poles, bars or tubes K having suspension clips L. The material 15 thus passes through the machine continuously and the requisite condition is obtained. An ordinary lifting device, as for instance wheels M and chains N, is provided to convey the material from the forward to the 20 return part of the chains J.

The machine is preferably incased with fireproof material arranged in the form of an outer casing and an inner lining. The outer casing is provided with port-holes (not 25 shown), and thus the suction side of the fan or blower D receives the necessary amount of fresh air to replace the moist air exhausted from the machine, and gathers the heated air which is radiated by the inner lining, 30 thus keeping the outer casing cool. A bulkhead O divides the suction side from the pressure side of the machine.

The machine is driven by cones P in conjunction with a double set of fast and loose 35 pulleys Q to enable the speed to be varied as desired. Sliding shutters R and doors S are provided to divert the discharge of the fan or blower D away from the machine when necessary.

40 The machine is made in various propor-

tions and sizes so as to be adapted to any requirement.

My improved machine has the following particular advantages:—simplest mechanical arrangements, minimum cost of construction, minimum floor space, minimum steam and power required, fireproof construction, easy access to all parts, maximum output, and comfortable working conditions. 45

I claim:

1. A machine of the type described for sammying and drying leather, and for drying yarns, jute, and the like, comprising a long horizontal drying chamber, means for longitudinally traversing the material in 50 forward and return directions through said chamber; an air-pressure inlet duct extending from end to end of said chamber, an air-suction outlet duct extending from end to end along the opposite side of said chamber, two flat sets of steam or other coils interposed between said chamber and said suction and pressure ducts respectively, a fan adapted to create a closed continuous circulation of air passing between said coils 55 and through both lines of material in said chamber, and means for continuous extraction of moisture from the closed circulation of air within said chamber, substantially as herein set forth. 60

2. Apparatus as claimed in claim 1, and having between each adjacent pair of tubes forming the coils a baffle plate whereby the circulating air is directed through the drying chamber and whereby a certain pressure 75 is held back in the air inlet duct so as to equalize the cross-current of air throughout the entire length of the chamber, substantially as herein set forth.

CHARLES STEPHENS.
